UNITED STATES PATENT OFFICE.

FRANK CORBETT, OF NEW YORK, N. Y.

IRONING-MACHINE.

SPECIFICATION forming part of Letters Patent No. 324,088, dated August 11, 1885.

Application filed July 3, 1884. (No model.)

To all whom it may concern:

Be it known that I, FRANK CORBETT, of the city, county, and State of New York, have invented certain new and useful Improvements 5 in Steam-Power Ironing - Machines, of which the following is a full, clear, and exact description.

Reference is to be had to the accompanying drawings, forming part of this specification, in 10 which similar letters of reference indicate corresponding parts in all the figures.

Figure 1 is a front elevation of my improved ironing - machine, parts being broken away. Fig. 2 is a sectional end elevation of the same 15 taken through the line $x x$, Fig. 1. Fig. 3 is an end elevation of the upper part of one end of the frame, parts being broken away and others shown in section. Fig. 4 is a front elevation of the same, partly in section.

20 The object of this invention is to facilitate the ironing of collars, cuffs, towels, table-cloths, and other articles.

The invention consists in certain novel constructions, combinations, and arrangements of 25 parts, as will be hereinafter described and claimed.

With the end frames and the hollow journals of the upper roller are connected half-bearings attached to perforated plates, having 30 loose plates between their upper ends, to which are swiveled crank-screws, and between which and the half-bearings are interposed springs, whereby the said upper roller can be readily adjusted to give any desired pressure to the 35 goods.

The machine is provided with a guide, extending over the upper roller and projecting forward beneath the lower roller, whereby the goods passed between the rollers will be 40 returned to the front of the machine, as will be hereinafter fully described.

A represents the end frames of the machine, which are connected by bars B, riveted or bolted to them.

45 C D are two hollow metallic rollers, cast with tubular journals, and which are designed to be plated with tin, or other suitable material that will not rust, and may be covered with several thicknesses of muslin, or other 50 suitable cloth.

To the journal of the lower roller, C, at one

end of the machine, is attached a pulley, E, to receive a belt from any convenient power. To the journals of the rollers C D, at one end of the machine, are connected the ends of a 55 short tube, F, of rubber or other suitable material, by swiveled couplings G, so that the said rollers will be free to revolve. With the other journals of the rollers C D are connected, by swiveled couplings G, tubes H, of rubber 60 or other suitable material, for the entrance and escape of steam to heat the rollers. The other ends of the tubes H can be connected with the steam-space of a boiler or other steam-generator. The journals of the lower roller, C, revolve in stationary bearings in the end frames, A. The upper roll has its trunnions journaled in movable bearing-frames. These bearing-frames are held and movable within the standards A, and have side plates, K K, provided 65 70 in their lower ends with half-round bearings. Between these plates I secure by bolts, J, the blocks I, which also have half-round bearings fitted on the opposite sides of the trunnions from the bearings in the plates K, and furnishing a complete bearing for such trunnion. The upper ends of plates K are connected by bolts L. A plate, M, is fitted and movable 75 vertically between the bolts L, and to its under side I secure, usually by rivets, as shown, a wider plate, N, which extends laterally under the bolts L. Between these plates M N, I form a hole or bearing for the enlarged end of the adjusting-screw, presently described.

O are crank-screws, which pass through 80 screw-holes in the cap-plates of the frames A, pass through holes in the centers of the plates M, and have enlarged ends P, attached to their lower ends, fitting into recesses formed to receive them in the adjacent faces of the plates 85 M N, so as to journal the said screws to the said plates. Between the plates N and the half-bearings I are placed rubber blocks Q or other suitable springs. With this construction 90 by turning the crank-screws O in one direction the plates M N will be raised, and the plates N coming in contact with the bolts L will elevate the bearing-frames and with them the upper roller, D. By turning the crank-screws O in the other direction the plates M 95 N will be forced downward, compressing the springs Q, so that any desired amount of press-

ure can be given to the cloth passing between the rollers C D. The roller D, it will be seen, may be pressed upward against the tension of the spring, because the upper end of the 5 bearing-frame may be raised above the plates M N, as will be seen.

R is a guide formed, preferably, of a plate of block-tin or other suitable sheet metal, which is curved to pass over the upper roller, D, pass 10 down at the rear side of the two rollers, and project forward beneath the lower roller, C, so as to return to the operator at the front of the machine the goods that have passed back between the said rollers. To the end edges of 15 the guide R are soldered or otherwise secured end plates, S, which are provided with suitable openings for the trunnions of the rollers. On the lower forward edge of the guide R is formed or secured a flange or plate, T, which 20 projects upwardly and forms a pocket to receive and prevent the goods from sliding off the said guide and falling to the floor in case the operator should not be ready to remove them as they are delivered at the lower-edge 25 of the guide R. If desired, two doors, R', can be formed, as shown in Figs. 1 and 2, in the guide R in such positions that they can be opened inward to rest against the lower roller and guide the goods out at the rear side of 30 the machine; or one of the doors R' can be opened and the other closed, so that collars and other articles that require to be passed several times through the machine can be 35 passed through opposite the closed door R' and delivered in front as many times as desired and then passed through opposite the open door and delivered at the rear side of the machine. It is for this purpose I prefer to employ two doors and arrange them laterally to 40 each other, as shown in Fig. 1, by which construction it will be seen articles may be passed simultaneously through the rollers, and one returned to the front and the other discharged at the rear by opening one of the doors and 45 letting the other remain closed. It will also be seen that the doors are pivoted below and in a plane between the vertical planes of the lower roller and the stop r of the guide against which the door rests when closed, by which

arrangement the door will remain, of its own 50 gravity, in either position to which it may be adjusted.

Having thus described my invention, what I claim as new, and desire to secure by Letters Patent, is—

55

1. The combination, with the ironing-rolls, of the return-guide extended up on the rear side of the rolls to a point above the plane of contact thereof and having its lower end extended and inclined forward below such rollers, and a plate, T, projected upward from the forward lower edge of the guard, forming a pocket whereby to retain the ironed articles, substantially as set forth.

2. In an ironing-machine, the combination, 65 with the end frames, A, and the hollow journals of the upper roller, D, of the half-bearings I, the perforated plates K, the swivel-plates M N, the crank-screws O, and the springs Q, substantially as herein shown and described, 70 whereby the said upper roller can be readily adjusted to give any desired pressure to the goods, as set forth.

3. The combination, with the ironing-rolls, of the return-guide having a plurality of doors 75 R', arranged laterally to each other and capable of being independently operated, whereby articles passed simultaneously through the machine may be delivered one to the front of and the other discharged in the rear of the 80 machine, substantially as set forth.

4. In an ironing-machine, the combination, with the lower roller and the guide having a doorway or opening and provided at the upper end of said opening with a stop, r, of the 85 door R', hinged at its lower edge to the lower edge of the opening in the guide and having its other edge adjustable against the stop r or against the lower roller, the hinge of said door being located in a vertical plane midway between those of the roller and the stop r, whereby it will remain by gravity in either of its 90 adjustments, substantially as set forth.

FRANK CORBETT.
